UNITED STATES PATENT OFFICE.

HALL H. HOLDAWAY, OF SALT LAKE CITY, UTAH, ASSIGNOR TO FRANKLIN SPENCER,
JR., OF LOS ANGELES, CALIFORNIA.

BUTTON-SEWING ATTACHMENT.

1,108,074.

Specification of Letters Patent. Patented Aug. 18, 1914.

Application filed April 21, 1913, Serial No. 762,725. Renewed July 6, 1914. Serial No. 849,244.

To all whom it may concern:

Be it known that I, HALL H. HOLDAWAY, a citizen of the United States, residing at Salt Lake City, in the county of Salt Lake 5 and State of Utah, have invented a new and useful Button-Sewing Attachment, of which the following is a specification.

This invention relates to attachments for sewing machines to facilitate the sewing of buttons onto goods or fabric.

The main object of the invention is to provide a device of great simplicity and effectiveness for this purpose.

Another object of the invention is to provide a button sewing device, which is adapted to sew buttons by diagonal stitches.

Another object of the invention is to provide a button sewing device which can be set to different operative positions so as to 20 sew the button either by diagonal stitches or by straight cross stitches.

Another object of the invention is to provide for adjustment of the length of the stitch in accordance with the distance between the holes in the buttons.

A further object of the invention is to provide for adjustment of the operating connections to enable the proper operation of the device by needle bars of different machines, having various limits of stroke.

Another object of the invention is to provide for adjustment of the device on the sewing machine table.

Other objects of the invention will appear hereinafter.

The accompanying drawings illustrate an embodiment of my invention, and referring thereto: Figure 1 is a plan view of the attachment. Fig. 2 is a section on line x^2-x^2 , Fig. 1. Fig. 3 is an end view of the attachment, showing the needle bar and machine table. Fig. 4 is a vertical section on line x^4-x^4 , Fig. 1. Fig. 5 is a horizontal section on line x^5-x^5 , Fig. 2, showing the supporting plate, the work holder and the operating means for producing and controlling the reciprocating movements of the work holder, showing the parts set to position for producing a diagonal stitch. Fig.

50 6 is a view similar to Fig. 5, showing the parts set for producing a diagonal stitch crosswise to that produced by the setting of Fig. 5. Fig. 7 is a section on line x^7-x^7 , Fig. 1. Fig. 8 is a plan of the controlling disk removed from the attachment.

1 designates a base or supporting plate which is adapted to be secured on the table 1^a of the sewing machine in any suitable manner, for example, by engagement of a pin 2 on base plate 1 with a suitable socket 60 2^a in said sewing machine table, and by engagement of the presser bar 3^a on the head of the sewing machine with a bracket 3 mounted on the plate 1. Said plate 1 is formed with a slot or opening 4 beneath 65 and adjacent to the position occupied by the needle bar x of the sewing machine to allow passage and movement of needle y in the operation of the sewing machine.

A work holder is provided in the form of 70 a bar or strip 6 connected by a pivot 7 at one end to an operating lever 8 which is fulcrumed at 9 as hereinafter set forth, and is oscillated by suitable means for producing a reciprocating movement of the work holder 75 along a line b , b . A clamp lever 5 is pivotally mounted on bar 6 and has its outer end portion 5' bent down close to the outer end portion 6' of bar 6, a spring 10 acting on bar 6 and lever 5 so as to force the portion 5' 80 toward the portion 6', the portions 5' and 6' acting as jaws or gripping members for the fabric d and button e , and being provided with slots or openings 17 for passage of the needle. Said slots or openings 17 85 register with one another and are preferably H-shaped, with notches 17' at the corners so as to provide maximum bearing surface for the work, while forming a passage for the needle and thread in all positions of the 90 work holder. Means are provided for guiding said work holder in such a manner that the work carried thereby will be reciprocated along the line of reciprocation b , b , or diagonal thereto as desired. For this purpose 95 the bar 6 is provided with a pin 11, which extends down through a slot 12 in a disk 13 which occupies and is rotatable in a circular hole 14 in the base plate 1, being retained in said hole by means of an upset flange 15 at 100 the bottom of said disk, and by an outwardly extending flange 13' at the top of the disk. Said disk is provided with a handle 16 whereby it may be turned to different angular positions so as to cause the slot 12 to extend in alignment with the line b , b , of reciprocation of the bar 6 or diagonal to the said line as hereinafter explained, and a locking device or dog 18 is provided for holding the said disk in either one of these 110

positions, said dog being pivoted to base 1 and having a V shaped tooth 18' adapted to releasably engage in any of a series of notches 19 in the edge of flange 13' of said disk, a spring 20 operating on said dog to force the tooth or projection 18' into engagement with the notches in the disk, so as to prevent accidental displacement, and yet permit the disk to be set to any point by manipulating handle 16.

The fulcrum 9 for the operating lever 8 is preferably adjustable lengthwise of said lever to shift the pivotal point and thereby vary or adjust the throw of the work holder. 15 For this purpose said fulcrum 9 is carried by an arm 23 pivoted at 24 on the base and having a handle 25 for operation thereof, and provided with a downturned lug 26 adapted to snap into any one of the series of 20 notches 27 on the base to hold the fulcrum in set position. Said fulcrum works in a longitudinal slot 29 in the lever 8 so that in any position of the fulcrum the lever 8 will engage with said fulcrum so as to rock 25 thereon. Such rocking movement of the lever 8 is produced by an operating yoke or anchor 30 pivoted at 31 to the base and pivotally connected at 32 to the lever 8, said anchor having arms or projections 33, 34 30 adapted to engage with the periphery of a star wheel 39 mounted on a shaft or pivot stud 40 on the base 1. Attached to said star wheel 39 is a ratchet wheel 42 engaged by a pawl 43 carried by shaft 44 journaled in 35 brackets 45, 45' on the base 1, said pawl 43 being operated by a spring 47 so as to hold it in engagement with the ratchet wheel while permitting the pawl to ride outwardly in its backward movement over the ratchet wheel. 40 A retaining pawl 46, operated by spring 48 is provided for ratchet wheel 42. A spring 49 is connected to shaft 44 and to the fixed bracket 45 so as to turn the shaft back to normal position. Said shaft is adapted to be 45 operated by the needle bar α of the sewing machine by means of an arm 50 on said shaft which is adapted to engage with a suitable part such as a screw α on the needle bar, and is adjustably connected to the shaft by means 50 of a clamp screw 51 on said arm engaging in a slotted arm 52 rigidly mounted on the shaft 44.

The operation is as follows: The attachment having been secured in place on the 55 table of the sewing machine, as above described, the clamp lever 5 is depressed at its handle portion 21, so as to raise the grip portions 5' thereof and the fabric and button to be sewed thereto are then inserted 60 between the grip or clamp portions 5' and 6' and the clamp lever then released so as to allow the spring 17 to force the clamp portion 5' down onto the button and hold the button firmly in position on the fabric 65 during the sewing operation. If a straight

cross stitch is desired, the controlling device 13 is placed in position shown in Fig. 1, and in the normal position of the parts, the bar 6 is at the extreme right hand position. The operator will first set the fulcrum lever 23 in position to give the proper throw to the work holder so as to reciprocate the button crosswise the distance between the two button holes, the button being so placed in the holder that when the 70 reciprocation of the bar 6 is at one end of its stroke, one of the button holes is brought under the needle and when the bar is at the other end of its stroke, the other button hole is brought under the needle. The 75 sewing machine is then started in operation, causing the arm 50 to be raised at each upward movement of the needle bar of the sewing machine and to be lowered in the downward movement of the needle bar by 80 operation of the spring 49. The resultant 85 rocking motion of the shaft 44 operates through the pawl 43 to turn the ratchet wheel 22 one tooth at each upward movement of the needle bar, the pawl slipping 90 idly over the ratchet wheel in the return movement. The star wheel 39 is thereby moved step by step, each movement being equal to one half the distance between the 95 projections of the star wheel and the operating anchor 30 is thereby caused to rock on its pivot 31 by engagement of the projections 33 and 34 of said anchor with the projections of the star wheel. Pivotal connection 32 of the anchor with the lever 100 38 is thereby moved back and forth, causing the lever 38 to rock on its fulcrum 9 and to reciprocate the bar 6 through a stroke whose length depends on the setting of the fulcrum 9. The controlling device 13 being placed in position to bring the slot 12 therein in alignment with the line b , b , of reciprocation of the bar 6, said bar is given a direct reciprocating movement at all parts 105 thereof, including the clamping or work holding portions 5' and 6' and the work, including the fabric and button, is thereby caused to move back and forth, so as to bring the two button holes of the button 110 alternately under the needle. After each 115 stroke of the work holding bar in this manner the bar is stationary for a moment, while the needle bar is passing downwardly and during a portion of the upward stroke, 120 so as to allow the needle to pass down through the button hole and fabric and make the stitch. The next movement of the bar 6 carries the work under the needle bar so as to draw the thread across from one button hole to the other, this operation 125 being repeated until a sufficient number of cross stitches have been made. The operation so described is especially adapted for two-hole buttons. In four-hole buttons, two cross stitches may be made by setting the 130

button first for one row of stitches and then for another, but I prefer in sewing four-hole buttons to use diagonal stitches, as but one setting of the button is then required and the operation is much more expeditious, the cross diagonal stitches also giving a better fastening for the button. In this case the button is set in position between the clamping members 5' and 6' with the respective button holes in the four notches 17' of the slot 17. The controlling device 13 is then moved by its handle 16 to position to place the slot 12 therein at an angle or obliquely to the line b , b , as shown, for example, in Fig. 5. The machine being then set in operation as above described, the reciprocation of the bar 6 causes the pin 11 to travel longitudinally in the slot 12 and by reason of the obliquity of said slot, said pin is given a lateral movement in its longitudinal operation and the lever 6 carrying said pin is thereby swung laterally so as to turn on its pivotal connection 7 to the operating lever 8 and to cause the outer 20 or gripping portion 6' of the lever, with the member 5' and the work held between said members, to swing laterally to the line of reciprocation of the bar 6, giving a compound movement whose resultant is an oblique or diagonal movement indicated by the dotted line c , c , in Fig. 5, the work holding member moving between the extreme positions shown in full and dotted lines in said figures. The position of the 30 needle bar remaining as indicated at y in said figure, the result of this operation is to cause a stitch to be effected alternately in diagonally opposite corners of the slot 17, the length of the stroke being adjusted 35 by setting the fulcrum lever 23 so that this diagonal movement carries the stitch from one button hole to the other. When sufficient stitches have been made along this line, the controlling device 13 is shifted to 40 a position shown in Fig. 6 and then operates to guide the work holding bar so as to cause it to move between extreme positions shown in full and dotted lines in said figure and to sew a stitch along diagonally across 45 the button transversely to the stitches first sewed.

In order to enable attachment of the device to different sewing machine tables, the pin 2 is movably mounted on base plate 1, 55 said pin being screwed or otherwise secured in any one of a series of holes 54 in plate 1.

To attach the bracket 3 to presser bar 3^a, a screw 22 on bar 3^a engages with a slot 3'.

What I claim is:

60 1. A button sewing device comprising a base, a work holder provided with means for clamping the button to the fabric, an operating device mounted on said base and connected to said work holder to reciprocate the same, and a controlling device provided

with guide means, and means on the work holder coöperating with said guide means to move the work holder laterally with respect to the line of reciprocation to give a diagonal movement to the work, said controlling device being pivotally mounted on said base so as to be angularly movable thereon independently of the motion of said work holder, and being provided with a handle for adjusting the same to vary the angular position of said guide means, and means for holding said controlling device in various adjusted positions. 70

2. A button sewing device comprising a base, a work holder provided with means for clamping the button to the fabric, an operating device mounted on said base and connected to said work holder to reciprocate the same, and a controlling device provided with guide means, and means on the work holder coöperating with said guide means to move the work holder laterally with respect to the line of reciprocation to give a diagonal movement to the work, said controlling device being pivotally mounted on said base so as to be angularly movable thereon independently of the motion of said work holder, and being provided with a handle for adjusting the same to set said guide means in alinement with the line of reciprocation, so as to eliminate the lateral motion, or to set said guide means angularly to one side or the other of said alined position to produce lateral movement in one or the other direction so as to provide 100 for crosswise diagonal movements of the work. 95

3. A button sewing device comprising a base, a work holder provided with means for clamping the button to the fabric, an operating device mounted on said base and connected to said work holder to reciprocate the same, and a controlling device provided with guide means, means on the work holder coöperating with said guide means to move the work holder laterally with respect to the line of reciprocation to give a diagonal movement to the work, said controlling device being pivotally mounted on said base so as to be angularly movable thereon independently of the motion of said work holder, and being provided with a handle for adjusting the same to set said guide means in alinement with the line of reciprocation, so as to eliminate the lateral motion, or to set said guide means angularly to one side or the other of said alined position to produce lateral movement in one or the other direction so as to provide 110 for crosswise diagonal movements of the work, said controlling device being pivotally mounted on said base so as to be angularly movable thereon independently of the motion of said work holder, and being provided with a handle for adjusting the same to set said guide means in alinement with the line of reciprocation, so as to eliminate the lateral motion, or to set said guide means angularly to one side or the other of said alined position to produce lateral movement in one or the other direction so as to provide 115 for crosswise diagonal movements of the work, said controlling device being pivotally mounted on said base so as to be angularly movable thereon independently of the motion of said work holder, and being provided with a handle for adjusting the same to set said guide means in alinement with the line of reciprocation, so as to eliminate the lateral motion, or to set said guide means angularly to one side or the other of said alined position to produce lateral movement in one or the other direction so as to provide 120 for crosswise diagonal movements of the work, and means for locking the controlling device in any of said positions. 125

4. In a button sewing device, a base plate having a circular hole, a disk rotatably fitting in said hole and provided with a slot 130

extending diametrically thereof, and with a handle for moving the same to different angular positions, means engaging with said disk for holding the same in different angular positions, a work holder slidably mounted on said disk and having a pin engaging in said slot to guide the work holder, and means for reciprocating the work holder.

5. In a button sewing device, a base plate having a circular hole, a disk rotatably fitting in said hole and provided with diametrically extending guide means, a work holder slidably mounted on said disk and provided with means engaging said guide means to control the direction of motion of

said work holder according to the angular position of said disk, said disk having notches in its periphery and being provided with a handle for adjusting it to different angular positions, and a spring dog on said base plate engaging said notches in the disk to hold the disk in adjusted position.

In testimony whereof, I have hereunto set my hand at Los Angeles, California, this 11th day of April, 1913.

HALL H. HOLDAWAY.
